DESIGN FOR A CLOCK CASE

Frank J. Abel, Massapequa, N. Y., assignor to Henry Hyman, Brooklyn, N. Y.

Application March 16, 1933. Serial No. 47,477

Term of patent 7 years

To all whom it may concern:

Be it known that I, FRANK J. ABEL, a citizen of Germany, residing at Massapequa, county of Nassau, and State of New York, have invented a new, original, and ornamental Design for a Clock Case, of which the following is a specification, reference being had to the accompanying drawing, forming a part thereof, in which Fig. 1 is a front elevational view of a clock case showing my new design and Fig. 2 is an edge elevational view of the same.

I claim:

The ornamental design for a clock case, as shown.

FRANK J. ABEL.
